TYMPANIC PNEUMO MASSAGE DEVICE

Filed July 25, 1932

INVENTOR:—
ARLYN T. VANCE.
BY *Martin P. Smith, Atty.*

UNITED STATES PATENT OFFICE

2,014,009

TYMPANIC PNEUMO MASSAGE DEVICE

Arlyn T. Vance, Los Angeles, Calif.

Application July 25, 1932, Serial No. 624,526

1 Claim. (Cl. 128—40)

My invention relates generally to therapeutic appliances and more particularly to a device for producing pneumo massage upon the tympanic membrane and the nerves associated therewith, also upon the ossicles and the external auditory meatus and the principal object of my invention is, to provide a relatively simple, practical and inexpensive device that may be conveniently employed for producing air pressure or partial vacuum within the auditory meatus and thereby impart gentle pneumo massage that is highly beneficial to all parts of the auditory canal, the tympanic membrane and nerves and to the osicular chain.

A further object of my invention is, to provide a tympanic pneumo massage device of the character referred to having graduated scales and means associated therewith for indicating the degree of pressure produced by the device while applying treatment to a patient and likewise the degree of applied vacuum and which pressure and vacuum it will be understood correspond respectively with the pressures prevailing below sea level and the decrease in pressure or rarity of the air in different altitudes above normal or sea level air pressure.

With the foregoing and other objects in view, my invention consists in certain novel features of construction and arrangements of parts that will be hereinafter more fully described and claimed and illustrated in the accompanying drawing in which:

Fig. 1 is an elevational view of a tympanic pneumo massage device constructed in accordance with my invention.

Fig. 2 is a vertical section taken through the upper portion of the hollow handle of the device and showing the air inlet and outlet opening therein.

Fig. 3 is an enlarged vertical section taken through the upper portion of one of the legs of the gauge tube and showing the air inlet and outlet opening therein.

Fig. 4 is an elevational view partly in section of that portion of the device that is applied to the outer end of the meatus or external auditory passage.

Referring by numerals to the accompanying drawing which illustrates a preferred embodiment of my invention, 10 designates a hollow cylindrical member that may be formed of metal, hard rubber or the like and which serves as a handle for the device and connected to a stem or nipple 11 that projects from the lower end of said handle, is one end of a small flexible tube 12. Con-

nected to this flexible tube is a bulb 13 of rubber.

Projecting upwardly from the upper end of the hollow handle 10, is a short tubular nipple 14 and formed through the wall thereof, is an aperture 15 that is surrounded by an externally arranged flange 16.

Secured to and projecting upwardly from stem 14, is a small tube 17, preferably of metal, and rigidly secured to the upper end of this tube is a tube 18, preferably of metal, that is slightly inclined with respect to the axis of tube 17.

Secured to the forward end of tube 18, is an applicator 19, preferably a small bulb of metal, hard rubber or the like and formed through the outer end of this applicator, is an aperture 20.

The rear end of tube 18, or the end opposite the bulb 19, receives a readily removable cap such as 21 (Fig. 4), or where the device is utilized with a pressure and vacuum gauge as illustrated in Fig. 1, one end of a flexible tube 22 is connected to the rear end of said tube 18.

The opposite end of tube 22 is connected to the upper end of one of the legs of an elongated U-shaped glass tube 23 and which latter is secured in any suitable manner to an upright panel 24 and said panel being supported upon a suitable base 25.

A small manually operable valve 26 forms a section between one of the legs of tube 23 and the flexible tube 22 and secured to the upper end of the other leg of the tube, is a tubular member 27, in the upper end of which is seated a screw 28.

Formed through the wall of tubular member 27 is an opening 29 and when the screw 28 is screwed into member 27 to its limit of movement, the inner portion of said screw closes said opening 29.

The lower portion of tube 23 contains a body of mercury and under normal conditions the level of this body of mercury in the two legs is approximately midway between the upper and lower ends 40 of the tube.

Appearing on the face of panel 24 in horizontal alignment with the level of the body of mercury within tube 23, is a zero mark 30 and appearing on the face of panel above this zero mark and adjacent to the leg of the tube to which flexible tube 22 is connected, is a scale that is graduated and marked so as to indicate increasing altitudes above sea level.

Appearing on the face of panel 24, below the zero mark 30 and adjacent to the leg of tube 23 to which flexible tube 22 is connected, is a graduated scale marked to indicate air pressures below sea level.

Appearing on the face of panel 24 above the zero

mark 30 and adjacent to the leg of tube 23 that carries the tubular member 27 and screw 28, is a graduated scale that indicates pounds of air pressure and appearing on the face of panel 24 5 below the zero mark 30 and adjacent to the leg of tube 23 that carries tubular member 27 at its upper end, is a graduated scale that indicates pounds of minus pressure or vacuum.

In the use of my improved pneumo massage 10 device, the bulb 19 is inserted snugly in the external auditory meatus and the thumb or finger of the hand that grasps the handle 10 is placed on rib or flange 16 so as to close aperture 15 and the rubber bulb 13 is now compressed, thereby 15 forcing air under pressure through flexible tube 12, handle 10 and tubes 17 and 18 into the external auditory passage and such pressure forces the tympanic membrane inwardly and produces movement of the ossicular chain.

20 To produce suction and consequent vacuum within the auditory canal, the thumb or finger is removed from aperture 15 and bulb 13 is compressed to discharge the air therefrom, after 25 which the bulb 19 is inserted in the entrance to the meatus and thumb or finger is positioned so as to close the opening 15 and as bulb 13 is permitted to expand, the suction through aperture 20 in bulb 19 and through the device will produce a partial vacuum within the auditory canal so as 30 to draw the tympanic membrane outwardly and produce corresponding movement in the ossicular chain.

The operations just described may be repeated alternately so as to apply pressure and partial 35 vacuum alternately within the auditory passage, with the result that the tympanic membrane, the ossicular chain and the nerves associated therewith will be gently massaged and thereby greatly benefited.

40 As bulb 13 is compressed to produce pressure as just described, air passing through tube 22 and into the upper portion of the leg or tube 23 to which said tube 22 is connected, will force the body of mercury downward through said leg and 45 upwardly through the leg that carries tubular member 27.

As the bulb 13 is permitted to expand after having been collapsed to produce suction or partial vacuum in the auditory canal, the body of mercury within tube 23 will lower in the leg that carries member 27 and will rise in the leg to which tube 22 is connected and by reading the levels of the body of mercury in the legs of said tube 23, the approximate pounds pressure or of vacuum 55 produced by the device and likewise the theoretical altitude or below sea level conditions may be readily observed.

60 The pneumo massage action produced by the device upon the tympanic membrane and ossicular chain is highly beneficial for the prevention of adhesions with diminished mobility of the sound conducting elements and also for the breaking down of adhesions already formed.

65 The gentle massage action produces a sedative effect upon subjective ear noises resulting from

severe chronic catarrhal otitis and also distressing tinnitus is greatly relieved.

Obviously the degrees of pressure and vacuum produced by the device in treatment should be governed by the patient's tolerance.

5 After the bulb 13 has been alternately compressed and released to bring about alternate pressure and suction as hereinbefore described, the treatment may be finished by first releasing all pressure on the bulb 13 and then quickly 10 removing the thumb from aperture 15 so as to permit sudden inrush of air through the device into the auditory canal. This action produces no pain and is extremely beneficial in restoring ossicular movement.

15 In the event that it is desired to use the device without the column of mercury and the indicating scales associated therewith, flexible tube 22 is detached from the end of tube 18 and a cap 21 is applied to the end of said tube, as illustrated in 20 Fig. 4.

When the panel 24 carrying the tube 23 is placed in a horizontal position, for instance, when the apparatus is packed for storage or transportation, valve 26 is closed and screw 28 25 is screwed down so as to close aperture 29 and thus the mercury within tube 23 is prevented from discharging from said tube.

30 Applicator bulb 19 tapers gradually from its intermediate portion toward its forward end in order that it may conveniently fit any external 35 auditory canal or meatus.

35 Thus it will be seen that I have provided a tympanic pneumo massage device that is relatively simple in construction, inexpensive of manufacture and very effective in performing the functions for which it is intended.

40 It will be understood that minor changes in the size, form and construction of the various parts of my improved tympanic pneumo massage 45 device may be made and substituted for those herein shown and described without departing from the spirit of the invention, the scope of which is set forth in the appended claim.

I claim as my invention:

45 In a tympanic pneumo massage device, the combination with a panel of a transparent U-shaped mercury containing tube positioned on the face of said panel, the face of said panel adjacent to the legs of said tube bearing a graduated pressure and vacuum indicating scale, a 50 hollow handle, a flexible tube connected to one end of said handle, a collapsible bulb connected to said flexible tube, a tube projecting from the other end of said handle, an applicator bulb carried by said tube, said bulb being provided with an orifice, a flexible tube connecting the end of one of the legs of the mercury containing tube with the bulb carrying tube at a point between 55 said bulb and said hollow handle, the upper portion of the other leg of the mercury containing tube being provided with an orifice and adjustable means for closing said last mentioned orifice.

60 ARLYN T. VANCE. 65
